DESIGN FOR A COMBINATION IDENTIFICATION SCRAPER AND KEY HOLDER

Cecil B. Woofter, St. Paul, Minn., assignor to
Brown & Bigelow, St. Paul, Minn.

Application May 23, 1947, Serial No. 139,242

Term of patent 14 years

(Cl. D9—6)

To all whom it may concern:

Be it known that I, Cecil B. Woofter, a citizen of the United States, residing in Saint Paul, county of Ramsey, and State of Minnesota, have invented a new, original, and ornamental Design for a Combination Identification Scraper and Key Holder, for which the following is a specification, reference being had to the accompanying drawings, forming part thereof:

Fig. 1 is a perspective view of a combination identification scraper and key holder showing my new design.

Fig. 2 is a left hand end view of Fig. 1.

Fig. 3 is a right hand end view of Fig. 1.

Figure 4 is a top plan view thereof.

Figure 5 is a bottom plan view thereof.

Figure 6 is a section on the line 6—6 of Figure 4.

The key chain has been omitted from all the figures, except Fig. 1, for convenience of illustration.

I claim:

The ornamental design for a combination identification scraper and key holder, as shown and described.

CECIL B. WOOFTER.
